UNITED STATES PATENT OFFICE.

THEODORE MELDER, OF ROXBURY, MASSACHUSETTS.

SECRET-LOCK BOX.

Application filed October 15, 1927. Serial No. 226,479.

This invention relates to improvements in lock boxes or receptacles and the principal object of the invention is to provide a secret-lock box in which the locking mechanism is wholly concealed from view from the exterior and which preferably also comprises mechanism for concealing the lock-actuating construction in such a manner that it cannot readily be detected.

More particularly the invention relates to boxes comprising a receptacle and a swinging cover and the object of the invention is to provide locking means movable into and out of locking engagement by relative movement of the cover and receptacle.

A further object of the invention is to provide a box of this character with a false bottom and providing means for detachably retaining said false bottom in place in such a manner that the removability of the false bottom is not apparent.

These and other objects and features of the invention will more fully appear from the following description and the accompanying drawings and will be particularly pointed out in the claims.

Various illustrative embodiments of the invention are shown in the accompanying drawings, in which,

Fig. 1 is a perspective view of a preferred form of rectangular secret-lock box;

Fig. 2 is a detail front view, on an enlarged scale, of supplemental locking mechanism for preventing relative sliding movement of the cover and receptacle;

Fig. 3 is a vertical sectional view of the supplemental locking mechanism illustrated in Fig. 2;

Fig. 4 is a vertical transverse sectional view of the box illustrated in Fig. 1, about midway of the length thereof, showing the cover in normal closed and locked position;

Fig. 5 is a sectional view, similar to that illustrated in Fig. 4, showing the cover slidably moved relatively to the receptacle to disengage the locking devices and ready to be swung to open position;

Fig. 6 is a longitudinal vertical sectional view on line 6-6 Fig. 4;

Fig. 7 is a fragmentary view of a portion of the under side of the cover and of the receptacle, illustrating the mechanism for permitting swinging and relative sliding movements of the cover and receptacle, and also showing the means for substantially conceal-

ing the mechanism for permitting such relative sliding movement;

Fig. 8 is a view of a modified form of the invention illustrating the receptacle in longitudinal vertical section with the cover in open position;

Fig. 9 is a transverse sectional view on line 9-9 Fig. 8 illustrating, however, the cover in closed position;

Fig. 10 is a view showing another embodiment of the invention illustrating the means for pivotally and slidably mounting the cover upon the receptacle, portions being illustrated in section;

Fig. 11 is a vertical sectional view on line 11-11 Fig. 10;

Fig. 12 is a view illustrating the invention as applied to a cigarette box, the members of which are illustrated in open position; and,

Fig. 13 is a broken transverse sectional view of the construction illustrated in Fig. 12.

The invention is illustrated in Figs. 1 to 6 inclusive as embodied in a rectangular box, such as a treasure chest, of wood, or other suitable material, having a bottom 1, and front and rear walls 2 and 3, and end walls 4 and 5. The cover 6 is of hollow form and is provided with a front wall 7, a rear wall 8, and end walls 9 and 10 which register with the walls 2, 3, 4 and 5 respectively. The cover is mounted upon the receptacle in such a manner as to permit swinging and relative sliding movements therebetween. Locking devices are provided which are adapted to interengage when the cover and receptacle are in normal position with the respective walls thereof in registry. These locking devices are adapted to be disengaged upon relative sliding movement of the cover to permit the same to be swung to open position and resilient means are provided to urge the cover toward, and maintain the same in, normal position.

In the particular embodiment of the invention shown in Figs. 1 to 6 inclusive, the locking devices comprise a hook 11 which is rigidly fastened to the front wall 7 of the cover and is adapted to engage a recess in a metal plate 12 which is secured to the inner face of the front wall 2 of the receptacle. The means for permitting swinging and relatively sliding movement between the cover and the receptacle comprises a hinge, or preferably a pair of hinges, a strap 13 of which is fixedly secured to the rear wall 3 of the

receptacle, and preferably extends over the upper edge thereof so that the pintle 14 is substantially in the plane of the rear wall 3. The other strap member 15 of the hinge is fixedly secured to a guide member 16, in the form of a block or plate, having tongued edges 17 which are slidably mounted in grooves 18 in the ends 9 and 10 of the cover. A complementary block 19 is located between the front wall 9 of the cover and the guide 16, and one or more helical springs 20 are interposed between the guide 16 and block 19 and tend to hold the cover in normal position illustrated in Fig. 4. These blocks 19 and 16 desirably are recessed to present respectively overlapping lips 21 and 22 and the overlapping portions are cylindrically recessed to receive the springs 20.

In the construction illustrated such guides are provided for each of a pair of hinges and the guides are connected by a bar 23 which is located adjacent the rear wall of the cover. A lining 24 for the cover is provided which substantially conceals the guides, the blocks, and the springs, so that the mechanism which permits relative movement between the cover and the receptacle is effectively hidden from view. By reason of this construction the locking devices are entirely concealed when the box is closed and the mechanism, which permits the opening of the box upon relative movement of the receptacle and cover, is effectively concealed when the box is open.

In the operation of the device, assuming it to be in locked position Fig. 4, to open the box it is only necessary to slide the cover rearwardly sufficiently to disengage the hook 11 from the recess in the plate 12, after which the cover can be swung about the pintle 14 of the hinge into open position. As soon as pressure upon the cover is released, the spring urges the cover toward normal position, so that when the box is to be closed and locked it is merely necessary to swing the cover to closed position with sufficient force to cause the inclined edge of the hook member 11 to force the cover rearwardly enough to cause its point to pass along the plate 12 and enter into registry with the slot therein. The spring 20 will then produce a forward movement of the cover which will force the point of the hook into the slot, thus automatically locking the cover in closed position.

As the manner in which the box can be opened will be obvious when once it has been demonstrated, supplemental locking means may be employed to prevent the relative sliding movement between the cover and the receptacle by any person other than one who is familiar with a particular setting of the supplemental lock. A simple and effective device for this purpose is illustrated in detail in Figs. 2 and 3 and comprises a plate 25 which is secured to the inner face of the front wall 7 of the cover and is provided with a

tongue 26 which projects below the lower edge of said front wall and is adapted to enter into a recess in the rear face of the front wall 2 of the receptacle. The lining 24 of the cover conceals this plate except for the projecting tongue thereof.

The co-operating locking member is in the form of a rotatable disk 27 having a radial slot 28 in its periphery adapted to be moved into or out of registry with the tongue 26 upon the cover member. The disk 27 is provided with a stem 29 which extends through the front wall of the box and preferably has secured to it a dial 30 having a knurled knob 31 by means of which the dial can be readily rotated. The dial may be provided with any sort of letters or numerals, one of which will indicate the registry of the slot 28 of the disk with the tongue, as for example, in the words "Captain Kidd's" upon the dial, as illustrated in Fig. 2, the letter "F" illustrates the registering position of the slot 28 with the tongue 26. When the tongues and slot are in registry relative sliding movement of the cover and receptacle is permitted. When, however, the tongue and slot are out of registry with the cover in closed position, relative sliding movement between the cover and receptacle will be prevented, so that the hook 11 cannot be released from engagement with the plate 12.

The slot 28 in the disk 27 may be positioned opposite different letters, numerals, or other indicia, for different boxes, so that a person knowing the proper letter of the dial to indicate the unlocking position of the supplemental lock of one box will not know the correct position of the supplemental locks of other boxes. A plurality of such supplemental locks may be provided, two being illustrated in Fig. 1 of the drawings.

A further feature of the invention comprises a false bottom construction which may further conceal certain contents of the receptacle. The construction illustrated in Figs. 4, 5, and 6, comprises a false bottom 32, the side edges of which slidably engage the front and rear walls 2 and 3 of the receptacle. The end wall 4 is provided with lining plates 33 and 34 which are secured to the adjacent edge of the wall with their adjacent edges separated to provide a groove 35 to receive one end of the false bottom 32. The opposite end wall 5 of the receptacle is provided with a lining comprising a detachable plate 36, the lower end of which is adapted to engage the other end of the false bottom 32. The upper edge 37 of the lining plate 36 desirably is beveled and engages an undercut complementary bevel upon an abutment or lining member 38 which is secured to the end wall 5 near its upper edge. A spring 39, or preferably a pair of springs, interposed between the bottom 1 of the box and the under face of the end of the false bot-

tom 32, which engages the detachable lining plate 36, normally holds the false bottom in the position illustrated. To remove the false bottom it is merely necessary to 5 depress the free end thereof against the action of the spring 39. The lining member 36 will drop sufficiently to disengage the upper edge from the abutment 38 so that the lining plate may be removed, whereupon the 10 free end of the false bottom can be lifted up and the false bottom removed. By reason of this construction a further safeguard for valuable treasures is provided.

In the construction illustrated the lining 15 members 34 and 38 are shown as extending upwardly above the edges of the ends 4 and 5 of the receptacle sufficiently to enter grooves 40 between the inner faces of the ends of the cover and the lining plate 24. By reason of 20 this construction additional rigidity is imparted to the box in closed position.

A modified embodiment of the invention is illustrated in Figs. 8 and 9 comprising a box of wood, or other suitable material, which 25 may be in all essential respects similar to that above described as indicated by the same numerals applied to similar parts of the box structure. In this modified construction, however, the end walls 9 and 10 are provided 30 with guide grooves 41 and 42 extending substantially the full length of said walls and a groove 43, extending preferably throughout the length of the front wall 7 of the cover. The guiding member 44, which is in 35 the form of a rectangular block or plate, is provided at its ends with tenons to engage the grooves 41 and 42, and at its front end is adapted to enter the groove 43 in the front wall 7. In this construction the hinge 40 desirably extends substantially the full length of the interior of the box and one strap 45 thereof is secured to the upper edge of the rear wall 3 of the box. The other strap 46 of the hinge is bent at right angles to lie against the inner face of the 45 rear wall 8 of the cover and has an offset end portion 47 which is secured by screws, or otherwise, to the block or guiding member 44. A leaf spring 48, which is located 50 within the groove 43, engages the front edge of the guiding member or block 44, and acting against said guiding member and the wall 7 tends to hold and to maintain the cover in normal position, while permitting a rearward sliding movement thereof as aforesaid. The lining 24 in this construction is of sufficient area to cover the entire inner surface 55 of the cover within the walls thereof and may be held in place by strips of moulding 49.

In this construction means are shown for limiting the movement of the cover when in open position. This comprises pairs of links 50 and 51 which are pivotally connected 60 respectively at their outer ends to the cover

and to the receptacle and pivotally connected together at their inner ends by a pintle 52. When the cover is closed down the links fold together with the hinge portion projected toward the interior of the box. Preferably 70 one of the links 50 has a projection extending beyond the end of the pintle and overlying the link 51 to prevent the links from folding toward the hinge of the box when the box is closed. 75

In this construction the lining member 44 for the cover, and also the lining member for the interior of the box, may be made of glass or porcelain, thus adapting the box 80 to be used as a humidor. In such case the lower portion of the box beneath the false bottom desirably is provided with a lining member 53 of aluminum, or other suitable material, resistant to rust and corrosion, to form a holder for a moistening pad. 85

A further modification of this construction resides in the resilient means for retaining the false bottom in place. As illustrated herein the false bottom 32, which is of glass or porcelain, is cemented, or otherwise secured, to an underlying plate or board 54 of wood. A leaf spring 55, which is seated in a socket 56, at one end of the box, slidably engages the under face of the board 54 and is guided thereupon by a suitable keeper 57. A curved leaf spring 58 which is secured by a keeper 59 at its central portion to the under surface of the free end of the plate or board 54, rests at its ends upon the bottom of the box 95 and supports the free end thereof against the lining plate 36, thus holding its beveled upper edge 37 in engagement with the abutment plate 38 as heretofore described. In this construction, as in that previously described, the lining member 36 may be released by depression of the free end of the false bottom and thereupon removed, thus permitting the removal in turn of the false bottom. This construction may, if desired, be provided with a supplemental locking device such as that 100 of the character heretofore described and may be operated in the same manner. 105

In Figs. 10 and 11 a modified construction is illustrated as applied to a metallic rectangular box, only a portion of the receptacle of which need be shown. In this construction the receptacle is a rectangular metal box, to the rear wall 60 of which straps 61 and 62 of the hinges are secured. The other straps 63 and 64 of the hinges are offset to lie normally in engagement with the inner face of the rear wall 65 of a hollow rectangular cover 66. The hinge straps 63 are again offset to provide extensions or guiding members 67 which extend well along the under face of the cover. A lining plate 68, also of metal, is secured to the inner face of the cover and is provided with recesses 69 and 70 to receive the extensions 67 and 68 of the straps 63 and 64. 115

The projections upon the front edges of the 120

lining plates may be inserted through suitable slots in the cover and riveted down to hold the cover in place and the ends of the lining plates may be provided with extensions bent downwardly to engage the inner faces of the end walls and projecting therebeyond to provide hooks 71 and 72 adapted to engage slots in complementary members upon the ends of the box. The rear edge of the lining member desirably is bent downwardly to form abutments 73 and 74 engaging a leaf spring 75, the ends of which engage respectively the offset portions of the straps 63 and 64. The lining plate of the cover is provided with recesses 76 and 77 to permit sufficient relative sliding movement of the cover and the guiding extensions 67 of the hinges to enable disengagement of the locking members in the manner heretofore described. In this construction, as in those previously described the spring urges the cover toward normal locking position and when the cover is closed upon the receptacle retains the hook 72 in locking engagement with the complementary members upon the end walls of the receptacle. When it is desired to open the box, the cover is moved rearwardly, thereby flexing the end portions of the spring 75 which engage the straps 63 and 64. This lateral sliding movement of the cover disengages the locking hooks 62 from their complementary members and permits the cover to be swung upwardly to open position as heretofore described.

35 Another modified embodiment of the invention is illustrated in Figs. 12 and 13 as applied to a metallic cigarette box. In this construction the receptacle and the cover are made of sheet metal pressed to hollow rectangular form of substantially identical size and depth, so that either member may be considered as the cover member. For convenience in comparison with the preceding embodiments of the invention the upper member 40 78 may be considered as the receptacle and the lower member 79 as the cover. The peripheral walls of the receptacle 78 are provided with an inwardly turned flange 80 to present an edge of considerably greater thickness than that of the metal of the receptacle. The central portion of the hinge wall is provided with an extension 81 which is bent into circular form to form the hinge member and to receive the pintle 82 of the hinge. The 45 other hinge members comprise cylindrically bent straps 83 and 84 which embrace the ends of the pintle 82 and are offset to engage the inner face of the rear wall 85 of the cover 79. These strap members may be formed as an 50 extension of a U-shaped frame the base 86 of which lies normally in engagement with the rear wall 85 of the cover and the legs 87 and 88 of which lie in proximity to the end walls 89 and 90 of the cover. The flanges upon 55 these end walls desirably are provided with

extensions 91 and 92 which lie in parallelism with the walls 89 and 90 and conceal the legs 87 and 88 of the U-shaped frame. The forward edge of the cover is provided with a hook member 93 which is adapted to engage 70 the flange 80 of the front portion of the base. A curved leaf spring 94 is held between the base 86 of the U-shaped frame and a tongue 95 upon a flange 96, which extends from the rear central portion of the rear wall forwardly and thence downwardly to embrace the spring 95. In this construction, as in those heretofore described, the sections of the case are normally retained in locked position by the action of the spring 94 which holds the walls of the edges of the sections in registry. To open the case it is merely necessary to cause sufficient relative sliding movement between the cover and the receptacle portion of the case to cause disengagement of the hook 93 from the flange 80, such relative sliding movement being permitted by the flexure of the spring 94. The parts of the case may then be swung to open position as illustrated in Fig. 12. To close the case it is merely necessary to swing the parts of the case into substantially closed position and then exert sufficient pressure to cause the flange 80 of the receptacle member to slide down the inclined face of the hook member 90 until the hook engages beneath the flange. Such compression will cause sufficient relative movement between the receptacle and cover members of the case to permit the device to lock automatically in the same manner as in 100 the constructions heretofore described.

It will be understood that the particular embodiments of the invention disclosed herein are of an illustrative character and are not restrictive and that various changes in form, 105 construction and arrangement of parts may be made within the spirit and scope of the following claims.

Having thus described the invention, what is claimed as new, and desired to be secured by Letters Patent, is:

1. A secret-lock box comprising a receptacle and a cover normally positioned to register therewith, concealed co-operating locking devices rigidly secured respectively to said receptacle and said cover, means connecting said cover to said receptacle operable to permit swinging and relatively sliding movements therebetween and resilient means acting to maintain said locking devices interlocked when the cover is in closed position, but yieldable upon relative sliding movement to permit the locking devices to be disengaged and the cover swung to open position.

2. A secret-lock box comprising a receptacle member and a cover member normally positioned to register therewith, concealed co-operating locking devices rigidly connected respectively to said receptacle member and to said cover member, a hinge rigidly

- fastened to one of said box members and slidably connected to the other box member and resilient means acting upon the movable box member to maintain said locking devices 5 interlocked when the cover is in closed position, but yieldable upon relative sliding movement of said box members to permit said locking devices to be disengaged and the cover swung to open position.
- 10 3. A secret-lock box comprising a receptacle member, a cover member therefor, concealed co-operating locking devices rigidly secured to said receptacle member and said cover member, a hinge having a strap rigidly fastened to one of said box members and a strap member slidably mounted within the other box member and resilient means acting upon the movable box member to maintain the locking devices interlocked when the cover is in closed position, but yieldable upon relative sliding movement of said members to 75 permit said locking devices to be disengaged and said cover swung to open position and means overlying and substantially concealing said strap member and resilient means.
- 15 7. A secret-lock box comprising a rectangular receptacle, a hollow rectangular cover therefor having peripheral walls normally positioned in registry respectively with like walls of said receptacle, co-operating locking members rigidly secured respectively to said receptacle and said cover, a hinge having a strap rigidly fastened to the rear wall of said receptacle, guiding means slidably mounted in ways in said cover, resilient means interposed between said guiding 80 means and a wall of said cover urging said cover toward normal position to cause interlocking of said locking means when the cover is in closed position, but yieldable to permit rearward sliding movement of said cover 85 relatively to said receptacle to disengage said locking means and to permit said cover to be swung to open position.
- 20 4. A secret-lock box comprising a receptacle and a cover normally positioned to register therewith, concealed co-operating locking devices rigidly secured respectively to said receptacle and said cover, means connecting said cover to said receptacle operable to permit swinging and relatively sliding movements therebetween and resilient means acting to maintain said locking devices interlocked when the cover is in closed position, but yieldable upon relative sliding 90 movement to permit the locking devices to be disengaged and the cover swung to open position and means selectively operable to permit or to prevent relative sliding movement of said members.
- 25 35 5. A secret-lock box comprising a receptacle member and a cover member normally positioned to register therewith, concealed co-operating locking devices rigidly connected respectively to said receptacle member and to said cover member, a hinge rigidly fastened to one of said box members and slidably connected to the other box member and resilient means acting upon the movable box member to maintain said locking devices interlocked when the cover is in closed position, but yieldable upon relative sliding movement of said box members to permit said locking devices to be disengaged and the cover swung to open position, supplemental locking means comprising a tongue member secured to one of said box members and a co-operating member rotatably mounted upon the other box member having a slot and means for selectively rotating said member to 100 position said slot into and out of registry with said tongue, whereby relative sliding movement between said box members may be permitted or prevented.
- 40 60 55 65 6. A secret-lock box comprising a receptacle member, a cover member therefor, concealed co-operating locking devices rigidly secured to said receptacle member and said cover, a hinge having a strap rigidly fastened to the rear wall of said receptacle and having guiding means slidably mounted in ways intermediate of said cover 105 110 115 120 125 130
- cealed co-operating locking devices rigidly secured to said receptacle member and said cover member, a hinge having a strap rigidly fastened to one of said box members and a strap member slidably mounted within the other box member and resilient means acting upon the movable box member to maintain the locking devices interlocked when the cover is in closed position, but yieldable upon relative sliding movement of said members to 75 permit said locking devices to be disengaged and said cover swung to open position and means overlying and substantially concealing said strap member and resilient means.
7. A secret-lock box comprising a rectangular receptacle, a hollow rectangular cover therefor having peripheral walls normally positioned in registry respectively with like walls of said receptacle, co-operating locking members rigidly secured respectively to said receptacle and said cover, a hinge having a strap rigidly fastened to the rear wall of said receptacle, guiding means slidably mounted in ways in said cover, resilient means interposed between said guiding means and a wall of said cover urging said cover toward normal position to cause interlocking of said locking means when the cover is in closed position, but yieldable to permit rearward sliding movement of said cover relatively to said receptacle to disengage said locking means and to permit said cover to be swung to open position.
8. A secret-lock box comprising a rectangular receptacle, a hollow rectangular cover therefor having peripheral walls normally positioned in registry respectively with like walls of said receptacle, co-operating locking members rigidly secured respectively to said receptacle and said cover, a hinge having a strap rigidly fastened to the rear wall of said receptacle, guiding means slidably mounted in ways in said cover, resilient means interposed between said guiding means and a wall of said cover urging said cover toward normal position to cause interlocking of said locking means when the cover is in closed position, but yieldable to permit rearward sliding movement of said cover relatively to said receptacle to disengage said locking means and to permit said cover to be swung to open position and means substantially concealing said guiding means and said resilient means.
9. A secret-lock box comprising a rectangular receptacle, a hollow rectangular cover having peripheral walls normally positioned in registry respectively with like walls of said receptacle, a lining in said cover, co-operating locking members rigidly secured respectively to like walls of said receptacle and said cover, a hinge having a strap rigidly fastened to the rear wall of said receptacle and having guiding means slidably mounted in ways intermediate of said cover

and lining and concealed thereby, a concealed spring interposed between said guiding means and a wall of said cover urging said cover toward normal position to cause interlocking of said locking members when the cover is in closed position, but yieldable to permit rearward sliding movement of the

cover relatively to the receptacle to disengage said locking devices and to permit said cover to be swung to open position.

10

In testimony whereof, I have signed my name to this specification.

THEODORE MELDER.
